LAPPING TOOL

David A. Wallace, Detroit, Mich., assignor to
 Chrysler Corporation, Highland Park, Mich., a
 corporation of Delaware

Application July 17, 1940, Serial No. 346,031

6 Claims. (Cl. 51—184.3)

My present invention is an improvement in mechanism for lapping or surface finishing the interior surfaces of cylindrical bores. The particular improvement has to do with means for varying the application of pressure upon the surface of the work by the lapping or abrading tools progressively from a higher pressure at the beginning of the finishing operation toward a lower pressure at the end of the finishing operation by means automatically releasing the pressure at a predetermined rate.

The principal object of the invention is to provide means whereby cylindrical surfaces may be finished to a greater degree of smoothness by a single tool which commences to operate with a greater degree of pressure upon the surface of the work and progressively operates at lesser pressures upon the surface of the work so as to provide means for smoothing down the abrasions caused by the tool itself as the pressure decreases. A second object of the present invention is to provide means for automatically timing the duration of the finishing operation, the function of the present invention being such as to decrease the pressure of the tool upon the surface of the work toward a final limit at which no work is done upon the interior surface.

These and other objects and advantages of the present invention will be apparent from the following specification taken in connection with the accompanying drawing which sets forth a preferred embodiment of the invention and wherein like numerals refer to like parts throughout.

In the drawing,

Fig. 1 discloses a finishing machine having a tool made in accordance with the present invention applied thereto;

Fig. 2 is an enlarged vertical section through the tool of the present invention; and,

Fig. 3 is a horizontal section taken substantially along line 3—3 of Fig. 2 looking in the direction of the arrows.

Referring to Fig. 1 there is disclosed a finishing machine comprising a bed plate 10 provided with rails 11 adapted slidably to guide a work-supporting cradle 12 in which is mounted the work piece 13 so as to permit shifting of the work piece to bring cylindrical bores, such as bore 14, therein in vertical alignment with the finishing tool 15. A standard 16 at the side of the bed plate 10 is provided with vertical tracks upon which is slidably guided a supporting member 17 which may be moved vertically by the application of fluid pressure to the cylinder 18 in which is mounted a piston 19 connected to the support-

ing member by connecting rod 20. Fluid pressure may be applied below the piston through pipe 21 in order to raise the supporting member, or above the piston through pipe 22 in order to lower it. Suitable valve means are provided to permit such raising and lowering operations, such valve means not being shown since they are well understood and from no part of the present invention. The supporting member 17 supports an electric motor 25 which is controlled by a switch operating lever 26 mounted upon the supporting member and movable therewith to engage a switch lever 27 extending from the control switch 28 mounted upon standard 16. As the piston 19 raises the supporting member, lever 26 engages lever 27 to stop the motor, and then through overriding provisions (not shown) passes above the lever 27. When the piston 19 lowers the supporting member, lever 26 reengages lever 27 to start the motor. The switching mechanism is not fully illustrated herein since such devices are well known in the art and form no part of the present invention.

Motor 25 is provided with an eccentric 30 which drives a connecting member 31, the lower end of which is pivotally fastened to a bearing ring 32 in which is rotatively retained the upper end of a spindle 33. The spindle 33 is splined so as drivingly to engage a gear 34 mounted in an extension of supporting member 17, while permitting reciprocation of spindle 33 through the hub of gear 34. Gear 34 is rotated by a worm gear 35 driven by a motor 36 mounted upon the supporting member 17. The spindle 33 is therefore rapidly reciprocated vertically by motor 25 and simultaneously rotated by motor 36. The lower end of spindle 33 is connected to a bifurcated tool carrying member 40, the arms of which are pivotally connected to a stirrup piece 41 having a cylindrical central bore in which is bonded a rubber member 42 having a smaller cylindrical central bore in which is bonded the hollow upper end of the elongated support 43 of the finishing tool 15.

The tool 15 comprises the support 43 in which is mounted an axially movable cylinder 44. The cylinder 44 is integrally closed at its upper end and is sealed at its lower end by a plug 45 having a packing gland 46 therein through which extends a piston rod 47 having its upper end connected to a piston 48 vertically slidable in the cylinder 44. The piston 48 is provided with a passage 49 in which a removable plug 50 is mounted, the plug being provided with a metering orifice which permits the escape of fluid from one

side of piston 48 to the other side. The plug 50 is screwed into the passage 49 and is provided with an orifice which is adapted to register with a bore 51 extending inwardly from the side of piston 48 and connecting with a bore 52 extending downward from the top of piston 48. The rate of escape of the fluid from the space above piston 48 to the space below piston 48 in the cylinder 44 may be varied by turning the plug 50 so as to cause a greater or lesser extent of the orifice therethrough to register with the bore 51. The piston 48 is also provided with a large orifice 53 extending therethrough in which is mounted a ball check 54 and spring 55 which tends to maintain the ball check in fluid checking position.

The upper end of cylinder 44 is connected to a plunger 60 which extends through a cap piece 62 threaded onto the upper end of support 43. The plunger 60 is provided with an elongated vertical slot 63 through which passes a crossbar 64 having its ends embedded in the cap piece 62. The lower end of the slot 63 is shaped to provide a lateral extension 65 in which the pin 64 may be engaged so as to hold the plunger 60 at its uppermost position when the plunger has been manually raised and rotated several degrees through the medium of the knob 66 at its upper extremity. Raising of the plunger 60 and connected cylinder 44 causes relative movement of the cylinder 44 and piston 48 which may be rapidly accomplished since the ball check 54 is raised from its seat so that all of the fluid quickly passes into the space above the piston 48. At the same time a spring 67 which extends between the cap piece 62 and the top of cylinder 44 is compressed to its greatest extent.

The rod 47 extends through a central bore in the lower end of the support 43 which is so shaped as to provide a support for a plurality of longitudinally extending natural or artificial abrading members. Preferably three such members are provided, of which members 70 and 71 are attached to the surface of the support in fixed relative position and member 72 is mounted in the support in a manner permitting radial movement thereof. The abrading members are preferably equally spaced about the circumference of the lower end of the holding support and are provided with arcuate surfaces to engage the cylindrical bore in which the tool is inserted. Member 72 is mounted upon a wedge-shaped holding member 73 slidably retained in a vertical slot in the member 43. The lower end of member 73 is yieldably retained by a leaf spring 74 fastened to the lower end of support 43 and overlapping the lower end of the member 73. The upper end of member 73 is similarly yieldably retained as by means of a garter spring 75 encircling the member 43. The rear face of the member 73 is engaged by the outer face of an operating wedge 76 slidably mounted in the support 43 and having its upper end attached to the rod 47. The lower end of the operating wedge 76 strikes an adjustable abutment screw 77 extending through the lower end of support 43 and adjustably limiting the downward travel of the operating wedge.

In using the tool the operator pulls upward on knob 66 and rotates it several degrees to engage crossbar 64 in the slot extension 65 in order to hold the plunger 60 inoperative until work is commenced. When the tool is lowered into the bore the knob 66 may be engaged and rotated to release the crossbar 64 from the extension 65, thus permitting the compression spring to move

cylinder 44. Since this creates a pressure upon piston 48 through the fluid trapped above the piston, pressure will be transmitted through rod 47 to operating wedge 76 to force abrading member 72 outward at a predetermined maximum pressure. The ball check 54 is held against its seat so that only a slight amount of fluid may escape through the metering device to the lower side of piston 48. As the fluid escapes, the cylinder 44 slides downward in the support 43 permitting spring 67 to expand. The pressure upon operating wedge 76 is thus progressively decreased, and also the outward pressure of members 70, 71, and 72 progressively decreases until finally there is no pressure being exerted since all the liquid will have escaped, or at least so much of the liquid will have escaped as entirely to decompress spring 67. By selecting the proper compression spring 67 and by determining the proper rate of escape of the fluid through the metering device, the initial force of the finishing tool upon the surface of the work may be set at a predetermined value and the rate of decrease of force and duration of the finishing operation may be fixed at desirable values.

Having described a preferred embodiment of the present invention, it should be apparent to those skilled in the art that the same permits of modification in arrangement and detail. All such modifications as come within the scope of the following claims are considered a part of my invention.

I claim:

1. A finishing tool for finishing the surfaces of cylindrical bores comprising an elongated support of lesser diameter than the diameter of the bore to be finished and provided with a surface finishing member extending radially beyond the surface of the support, a movable holding member for said finishing member which is slidably guided for radial movement with respect to said support, wedging means slidably guided in said supporting member in wedging contact with said holding member, a piston attached to said wedging means, a fluid-filled, sealed cylinder in which said piston is located and which is movably guided in said support and adapted to exert fluid pressure upon said piston when being moved toward said wedging means, and a metering device in said piston for permitting metered escape of fluid from one side of said piston to the other side when said cylinder is being moved toward said wedging means whereby to release said fluid pressure at a predetermined rate.

2. A finishing tool for finishing the surfaces of cylindrical bores comprising an elongated support of lesser diameter than the diameter of the bore to be finished and provided with a surface finishing member extending radially beyond the surface of the support, a movable holding member for said finishing member which is slidably guided for radial movement with respect to said support, wedging means slidably guided in said supporting member in wedging contact with said holding member, a piston attached to said wedging means, a fluid-filled, sealed cylinder in which said piston is located and which is movably guided in said support and adapted to exert fluid pressure upon said piston when being moved toward said wedging means, a metering device in said piston for permitting metered escape of fluid from one side of said piston to the other side when said cylinder is being moved toward said wedging means whereby to release said fluid pressure at a predetermined rate, and a compression

spring adapted to effect movement of said cylinder toward said wedging means whereby the pressure exerted upon said piston progressively decreases as said spring decompresses.

3. A finishing tool for finishing the surfaces of cylindrical bores comprising an elongated support of lesser diameter than the diameter of the bore to be finished and provided with a surface finishing member extending radially beyond the surface of the support, a movable holding member for said finishing member which is slidably guided for radial movement with respect to said support, wedging means slidably guided in said supporting member in wedging contact with said holding member, a piston attached to said wedging means, a fluid-filled, sealed cylinder in which said piston is located and which is movably guided in said support and adapted to exert fluid pressure upon said piston when being moved toward said wedging means, a metering device in said piston for permitting metered escape of fluid from one side of said piston to the other side when said cylinder is being moved toward said wedging means whereby to release said fluid pressure at a predetermined rate, a compression spring adapted to effect movement of said cylinder toward said wedging means whereby the pressure exerted upon said piston progressively decreases as said spring decompresses, means to move said cylinder in the opposite direction to compress said spring, and a check valve in said piston opening on such opposite movement to permit rapid return of the fluid in said cylinder to said one side of the piston.

4. A finishing tool for finishing the surface of cylindrical bores comprising an elongated support of lesser diameter than the diameter of the bore to be finished and provided with a plurality of circumferentially spaced, longitudinally extending surface finishing members extending radially beyond the surface of the support, a movable holding member for at least one of said finishing members which is slidably guided for radial movement with respect to said support, an operating wedge slidably guided in said support in wedging contact with said holding member, a piston attached to said operating wedge, a sealed, movable cylinder in which said piston operates and which is slidably guided in said support, a spring adapted to be compressed by relative movement of said movable cylinder and said support in one direction, and a metering device

5 in said piston to permit metered escape of fluid contained in said cylinder from one side of said piston to the other during relative movement of said cylinder and said support in the opposite direction by the decompression of said spring.

10 5. A finishing tool for finishing the surfaces of cylindrical bores comprising an elongated support of lesser diameter than the diameter of the bore to be finished and provided with a plurality of circumferentially spaced, longitudinally extending surface finishing members extending radially beyond the surface of the support, a movable holding member for at least one of said finishing members which is slidably guided for radial movement with respect to said support, and mechanism for causing such radial movement including a piston and a spring adapted to be compressed to exert a predetermined initial pressure through the medium of said piston to the surface finishing members, said mechanism including means for releasing the compression of said spring an amount in addition to the reduction in compression thereof resulting from abrading of said bore and at a predetermined rate during operation of said finishing tool whereby the pressure exerted by said surface finishing members progressively decreases as said spring approaches its normal length.

15 6. A finishing tool for finishing the surfaces of cylindrical bores comprising an elongated support of lesser diameter than the diameter of the bore to be finished and provided with a plurality of circumferentially spaced, longitudinally extending surface finishing members extending radially beyond the surface of the support, a movable holding member for at least one of said finishing members which is slidably guided for radial movement with respect to said support, means for causing such radial movement including a piston and a spring adapted to be compressed to exert a predetermined initial pressure through the medium of said piston to the surface finishing members, a cylinder in which said piston is slidable, and an orifice permitting regular escape of a fluid from one side of said piston to the other in said cylinder under compulsion of the force of said spring whereby the pressure exerted by said surface finishing members progressively decreases as said spring is released 20 from compression.
